Robert B. Pealer, Garrettsville, Ohio, assignor to
Beaver Pipe Tools, Inc., Warren, Ohio, a cor-
poration of Ohio

Application December 5, 1952, Serial No. 22,565

Term of patent 14 years

(Cl. D54—14)

To all whom it may concern:

Be it known that I, Robert B. Pealer, citizen of the United States of America, residing at Garrettsville, county of Portage, State of Ohio, have invented a new, original, and ornamental Design for a Power Drive Unit For Use With Hand Cutting Tools, of which the following is a specification, reference being had to the accompanying drawings, forming a part thereof:

In the drawings,

Fig. 1 is a front elevational view of a power drive unit for use with hand cutting tools showing my new design;

Fig. 2 is a rear elevational view thereof;

Fig. 3 is an elevational view showing the left side of Fig. 1; and

Fig. 4 is a front elevational view showing the power unit removed from the stand.

I claim:

The ornamental design for a power drive unit for use with hand cutting tools, as shown.

ROBERT B. PEALER.
